DESIGN FOR A BREAD SLICING BOARD

Ruel J. Richardson and John Terpstra,
Lynwood, Calif.

Application February 22, 1943, Serial No. 109,606

Term of patent 3½ years

To all whom it may concern:

Be it known that we, Ruel J. Richardson and John Terpstra, citizens of the United States, residing at Lynwood and Lynwood, respectively, in the county of Los Angeles and State of California, have invented a new, original, and ornamental Design for a Bread Slicing Board, of which the following is a specification, reference being had to the accompanying drawing, forming a part thereof.

In the drawing:

Fig. 1 is a front elevational view of a bread slicing board, showing our design;

Fig. 2 is a top plan view;

Fig. 3 is a rear elevational view; and

Fig. 4 is an end elevational view thereof.

We claim:

The ornamental design for a bread slicing board, as shown.

RUEL J. RICHARDSON.

JOHN TERPSTRA.
